SURFACE CHILLING MEANS FOR CASTINGS

Edwin A. Walcher, Lima, Ohio, assignor to The Ohio Steel Foundry Company, Lima, Ohio, a corporation of Ohio

Application April 17, 1944, Serial No. 531,326

2 Claims. (Cl. 22—127)

This invention relates to foundry practice, and particularly to the surface chilling of castings of large volume, such as iron and steel rolls of the type used in rolling mills.

It is generally believed that in a mold consisting of sand rammed into a steel flask, the process of solidification of a steel casting formed therein proceeds as follows: as the molten metal comes in contact with the mold wall, which has a temperature of from 100° to 200° F., there is an immediate chilling action upon the casting metal caused by conduction of heat to the mold wall which is in contact with the molten metal, and the shock in the meeting of these two substances having such a great difference in temperature causes a thin skin of solid metal to form almost immediately on the casting metal. This skin of metal forms progressively upward in the case, for instance, of a roll mold poured vertically with a gate in the bottom end of the mold, so that the molten metal as it rises in the mold swirls inside of a very thin casing of metal. In an ordinary mold, such as commonly used for the making of large mill rolls, this transfer of heat from the molten metal to the mold causes a certain amount of expansion in the mold itself. Because the outer portion of the mold retains its lower temperature for a time after pouring, the expansion of the mold must be inwardly until all of the mold walls have become substantially uniformly heated by conduction of heat from the molten metal. When this has occurred, the heat is removed from the exterior walls of the flask by transference to the surrounding atmosphere. By the time the mold and flask have become heated throughout, the interior surface of the mold has probably reached a temperature somewhere near that of the contacting metal which has become solid around the outer surface portion of the casting. As soon as the sand mold and flask have become heated throughout, outward expansion of the mold begins so that an air space forms between the casting and the interior mold wall, which space becomes a very effective insulating area against heat conduction. Consequently, the only chilling action on metal poured into an ordinary sand mold is that which is obtained in the short period which is required to bring the inner surface of the mold up to approximately the same temperature as the outer surface of the casting, which action must take place before the mold is heated throughout, or before an insulating air space can form between the mold wall and the surface of the casting.

Another recognized factor in the casting of 55

large bodies, such as steel rolls, is that the molten metal, which is subjected to chill, solidifies by forming an elongated crystalline structure; that these primary crystals undoubtedly form very rapidly and tend to push any non-crystalline and lower melting eutectic substances in the molten metal in toward the center of the casting; that the portion of the roll which solidifies in this manner is the best part of the roll for mill usage due to the uniformity of its crystalline structure, and that therefore it is important to drive these substances of lower melting point as deeply into the roll structure as possible. It is known that inside of the chilled rim portion of a roll casting, in the zone of equiaxial crystals, defects such as segregation lines, softness and lack of density will appear, and that the presence of these defects not only shorten the usable life of a roll but frequently renders a roll unsuitable for mill use when it is initially dressed down from its original diameter.

Many attempts have been made to accelerate the cooling rate for the working surfaces of roll castings so as to overcome these objections, but, so far as I am aware, without entire success. One method employs chill rings of metal, usually iron or steel, placed in a sand mold, at or closely adjacent to its inner wall, in those areas for which better wearing qualities are desired in the roll casting. This method is generally used in the casting of swept out pass rolls, the metal rings being made in shapes to correspond to the designs of the passes. These chill rings with flat surfaces are also frequently used along the entire length of the body in the casting of plain body rolls. With this method, the extent or depth of chilling action is dependent on the size of the chill rings. When the chill rings have attained a temperature somewhere in the neighborhood of the solidified outer rim of the roll casting, the transfer of heat from the casting proceeds in a similar manner to that for simple sand molds. Therefore, while this method is an improvement over the sample form in which sand alone is used, it has very definite limitations.

Another method consists in the use of a metal instead of a sand wall mold to effect more rapid conduction of heat from the casting to the atmosphere and thus accelerate the cooling rate for the rim portion of the roll casting over that effected by the use of sand molds. While this method is an improvement over the sand roll casting method in that the initial absorption of heat by the metal mold is carried on at a very rapid rate which quickly solidifies a heavy skin

of metal on the roll casting, this method is limited to the size of the mold walls and can only be used in the production of plain body rolls. Furthermore, the chilling of the primary crystalline structure cannot extend to any substantial portion in depth of the cross-section of the roll. For instance, in a roll thirty inches in diameter, which is cast at approximately thirty-one inches to allow some stock for finish, the depth of the primary crystalline structure is probably not more than two inches to three inches on a side, thus when it becomes necessary to remove the outer half inch of stock on each side during machining, it is seen that there will be only about one and one-half inches of good metal forming a rim around the roll casting, and that below this rim defects such as segregation lines, softness and lack of density will appear.

After practicing the above-noted methods, and recognizing the fact that chilling by such methods depended upon the transfer of heat to the outer atmosphere, and realizing that the rate of this transfer was somewhat slower than necessary to provide the desired results, as indicated by the fact that the interior surface of a chill mold remained quite hot, the idea of spraying the outside surface of a mold with water to expedite the transfer of heat was experimented with and some degree of success obtained. Out of this practice, which was unsuitable for very close control, developed the idea of providing molds with circulating water chills. This method, however, as heretofore practiced has its limitations and has not obtained the depth of hardness and uniform crystalline structure desired in large rolls.

The present invention relates primarily to improvements in the water circulating method wherein pipes carrying a circulating water are imbedded in the mold wall around the roll casting and in close relation thereto, and its object is to increase the chilling action of the casting and consequent conduction of heat therefrom over the methods heretofore employed, whereby to increase the depth of uniformity of crystalline structure in the roll body from the working surface inward and to consequently increase the life and wear characteristics of the roll.

Further objects and advantages of the invention will be apparent from the following detailed description and from the accompanying drawings illustrating two embodiments of the invention, and in which—

Figure 1 is a fragmentary perspective view of one-half of a mold embodying the water chill feature of the invention looking at the drag end of the chill, with a part in section and with the inner thin sand coating over the chill partly broken away; Fig. 2 is an enlarged perspective of a corner portion of a water chill unit, with a part broken away to disclose the communicating opening between the inlet header and a tube; Fig. 3 is an inner plan view of a water chill unit section, with parts broken away; Fig. 4 is an inlet end view of such chill unit section; Fig. 5 is a fragmentary vertical section of a mold including the combined water chill and ring chill features of the invention with a formed casting, parts of which are broken away, and Fig. 6 is a cross-sectional view on the line 6—6 in Fig. 5, with a part of the sand wall of the mold broken away.

The invention assumes two forms, one in which a water circulating means of improved construction is imbedded in the mold wall and produces increased and highly beneficial chilling results on the roll casting over those heretofore obtained,

while the other form combines both the water circulating and the ring chill methods to obtain such results and is used particularly in connection with the casting of swept out pass rolls, but is not restricted to such use.

In the first form of the invention, which is illustrated particularly in Figs. 1 to 4, the structure which carries and controls the movement of the cooling fluid (usually water, and hereinafter referred to as such) within the mold wall in close relation to its interior wall is composed of a plurality of spaced parallel tubes 10, preferably extending lengthwise of the mold and connected at their lower and upper, or drag and cope, ends by inlet and outlet headers 11 and 12, respectively. These tubes are of sufficient length to cover the body of the casting, and, in the case of a roll, the working portion thereof, which is desired to be dense and free of streaks and segregation.

20 The tubes 10, in the present instance, are square in cross-section, instead of round as has heretofore been the custom in connection with chills of this character, and each presents a substantially flat side longitudinal and tangential to a circle struck from the axis of the roll forming cavity of the mold, with a radial line thereof, which is normal to such side, intersecting the side at its center, as indicated at a in Fig. 4. This presents a fairly broad face to the roll surface and causes a more uniform spacing of a tube throughout its width from such surface than is the case with a round tube, thus resulting in a more uniform and deeper chilling of the roll metal.

25 30 35 The spacing of the tubes 10 from each other is preferably substantially equal to the width of the tubes, and the tubes are preferably imbedded in the sand wall of the mold an extent to provide a thin sand covering for the inner side of the tubes so that the tubes will not have direct contact with the roll metal. It has been determined in practice that by chilling a roll by the use of tubes of this character, the lower melting eutectics, such for instance as sulphur, metallic sulphides, phosphides, etc., in the casting metal, are driven more deeply into the roll so as to provide a greater depth of uniform grain structure from the outer surface inwardly of a roll than is obtained by the use of round tubes for the circulating water.

40 45 50 55 The headers 11 and 12 are also preferably of square tube form and the inlet header 11 is disposed in connecting relation around the adjacent ends of the tubes 10 at the sides thereof opposed to the casting, so that the connecting passages of the tubes with the header are at the outer sides of the tubes and radially disposed with respect to the casting. The outlet header 12 on the other hand is preferably disposed at the ends of the tubes substantially flush therewith with their connecting passages endwise of the tubes.

60 65 70 75 This disposition of the headers relative to the tubes 10 is to lessen the chilling action on the casting metal of the cooling water at the inlet header end where the water is the coldest and to increase the chilling action thereof on the casting metal at the outer header end where the water is the hottest. These headers, however, are usually positioned at the neck ends of a roll casting beyond its body ends, so that they are more remotely spaced from the casting metal than the tubes 10 and therefore, in such case, their positions with respect to the tubes are not of such great importance, although desirable. In practice, two inch square pipes have been used for

the headers while one and one-quarter inch square pipes have been used for the lengthwise tubes. It is not intended, however, to restrict the headers and tubes to any particular sizes.

The water chills, comprised by the tubes 10 and headers 11 and 12 with their connections, are preferably fabricated in two half circular sections, as shown so that they may be set in the two halves comprising the standard steel roll flask. In order to provide substantially uniform distribution of the water to the inlet header, the supply pipe 13 therefore has a three-way connection 14 therewith, with the connections substantially uniformly distributed throughout the length of the header section. Standard molding practice provides that, when used, these chills should be covered at the casting side of a mold wall with a layer of sand, the thickness of which depends upon the amount of chilling desired for the roll or other casting and upon the chemical analysis of that casting. As is well known in the casting industry, metals of high nickel and chrome content cannot be subjected to as drastic a chilling action as plain low carbon steels.

Where the castings to be made are of the swept out pass roll type, it is found that a hardened surface structure, improved both as to depth of hardness and uniformity of crystal, can be obtained over that produced by the use of the usual chill rings if a water chill is used in combination therewith in surrounding contacting relation to the rings. It is also found that these results are improved if a water chill having square or flat surfaced tubes as distinguished from round tubes is used.

Such a combination is illustrated in Figs. 5 and 6 in which the chill rings, designated 18, are set in the passes 19 of the roll, and the water chill sections, designated 20, are of the same square type tube construction as described in connection with Figs. 1 to 4. The water chill sections 20 are disposed within the mold wall around the chill rings 18, and both the water chills and the ring chills are usually spaced from the casting by a thin wall of sand as described in connection with the water chill alone. The rings 18 are usually quarter sectioned to facilitate assembly.

The chill rings 18, which usually are of cast steel, are placed in direct contact with the water chill sections 20 so that the heat abstracted from the molten casting is readily transferred through the rings to the water which is kept circulating under a pressure of approximately seventy-five pounds in the water chill piping. The constant flow of the water or other coolant under this pressure means that the heat is continually abstracted from the chill rings, and the effect of this chilling goes on until the entire roll casting has become solid. This action is facilitated by the flat contact of the chill pipes with the chill rings. The chill rings when used alone, as has heretofore been the practice, are not always a satisfactory medium for extracting the heat and controlling the grain structure of a casting, and particularly roll castings of large volume, because the rings are liable to become distorted under contraction and expansion. Also, the extent of the chilling action of these rings is dependent upon the size of the rings, and this size can never be very great, as has heretofore been pointed out. Also when these metal chills become saturated with heat they have little further chilling action, unless used in combination with cooling pipes containing a circulating coolant under pressure.

With the use of both forms of chills shown, which provide a deep chill effect on the rolling surfaces of roll bodies, there is danger in the abrupt change from the chilled portion of the roll body to the head or feeder portion on which it is not desirable to have any chilling action. In order to alleviate the drastic effect of this abrupt change in chilling conditions, a sectional chill ring composed of an annular series of spaced metal chill members 21 is used on the cope shoulder section of the mold. These chill members are spaced apart and are of decreasing thickness from their outer ends inwardly so as to distribute the chilling action at the end of the roll chill over a considerable portion of the roll neck by abstracting a gradually decreasing amount of heat from the roll neck as the size of the neck becomes smaller and transferring this heat to the water chill. Good results have been obtained by making these chill members about two inches wide with about two inch spaces therebetween, as indicated in Fig. 5. These dimensions, however, are merely illustrative and not in limitation of the invention. It is necessary to use a heavy cast chill 22 of ring-form at the drag shoulder of the mold, which, resting upon the water chill, becomes an effective heat removing agent so that directional solidification upwards is obtained in the casting at the adjacent neck shoulder, which is a highly desirable feature.

I wish it understood that my invention is not limited to any specific construction, arrangement or form of the parts, as it is capable of numerous modifications and changes without departing from the spirit of the claims, and also that while it has been more particularly described for use in casting mill type rolls, it is intended for use in connection with the making of any castings of considerable volume and for which it may be adapted.

Having thus described my invention, what I claim as new, and desire to secure by United States Letters Patent, is:

1. In a sand mold having a cavity for casting large swept out pass rolls, the combination with one or more ring chills in the mold wall to suit the roll passes, of a water chill set into the mold wall without said ring chills and having a plurality of transversely spaced parallel water circulating tubes disposed lengthwise of the mold with their inwardly facing sides substantially flat and in heat conducting contact with the outer sides of the ring chills, whereby the radial conduction of heat from the roll metal within the mold to the tubes is substantially uniform throughout the width of each tube at any cross-sectional edge thereof.
2. In a sand mold having a cavity for casting a large iron or steel roll having a reduced diameter cope end neck portion, the combination with a water chill in the mold wall, of a sectional chill set into the mold wall around said neck portion in close relation to its inner surface and in heat transfer contact at its inner side with said water chill, said sectional chill comprising an annular series of narrow spaced apart chill members following the contour of the neck forming portion of the mold from the roll body in a radial direction and gradually decreasing in thickness inwardly from its water chill contacting surface end.

EDWIN A. WALCHER.
